UNITED STATES PATENT OFFICE.

BROOK SYKES, OF TORONTO, ONTARIO, CANADA.

CALENDAR.

1,251,838.

Specification of Letters Patent.

Patented Jan. 1, 1918.

Application filed September 2, 1916. Serial No. 118,309.

To all whom it may concern:

Be it known that I, BROOK SYKES, of the city of Toronto, in the county of York, in the Province of Ontario, in the Dominion of Canada, have invented certain new and useful Improvements in Calendars, and do hereby declare that the following is a full, clear, and exact description of same.

This invention relates to calendars adapted to form an attachment for a telephone for the convenience of telephone users and has therefore for its object to provide an article of utility of this type which may be readily attached to the usual kind of telephone while being capable of use as a wall or general calendar if so desired.

Further objects are to provide simple and efficient means for effecting the securing of the calendar against inadvertent displacement when positioned upon a telephone. Still further objects subsidiary to or resulting from the above objects or from the construction of the calendar as hereinafter described will become apparent as the invention is further disclosed.

In carrying the invention into effect I prefer to employ a rotary date disk suitably inscribed and divided into the various months, said disk being located and supported within an outer casing and provided with a central orifice registering with a central orifice in said casing, these orifices being of sufficient size to permit the entering thereinto of the mouthpiece of the telephone when said calendar is positioned upon said phone and means being preferably provided in proximity to said orifice, to resiliently grip said mouthpiece for the purpose of preventing the rotation of said casing about said mouthpiece. Further means may also be employed to secure the said casing against moving in forward direction above the said mouthpiece if thought necessary or desirable; all of which is more particularly described in and by the following specification, having reference to the accompanying drawing in which:

Figure 1 is a perspective view of part of a telephone having the calendar affixed thereto.

Fig. 2 is a detail elevation of the said calendar, and

Fig. 3 is a transverse vertical section of the said calendar, the telephone being shown in its relation thereto in dotted lines.

Figs. 2 and 3 are drawn to a somewhat larger scale than Fig. 1.

Similar characters of reference indicate similar parts in the several figures of the drawing.

In the example illustrated is the transmitter casing of a desk telephone having the usual rim 2 and carrying the detachable mouthpiece 3 in the manner well known.

As an article of utility it is proposed to apply a calendar, preferably of that type known as a rotary calendar, to the said transmitter casing whereby said calendar or the parts associated with said calendar will be disposed around the said mouthpiece and so be in a convenient position for reference when the telephone is in use and also by virtue of the fact that a telephone is generally located in a readily accessible position.

4 and 5 are front and rear plates forming collectively a casing inclosing a rotary date disk having the several months or other information printed or otherwise inscribed thereon, the said front plate 4 of the casing 4, 5 being suitably orificed as at 7 to permit the viewing of such portion of said disk 6 as may register with the said orifice 7, the said disk being capable of rotation to bring various portions of its surface into juxtaposition with said orifice 7.

The casing 4, 5 and the disk 6 are centrally orificed, said orifice being of sufficient diameter to admit of the passing therethrough of the smaller end of the said telephone mouthpiece, so that when the calendar is located upon a telephone, as shown in Figs. 1 and 3 of the drawing, the smaller end of said mouthpiece 3 in proximity to the transmitter casing 1 will be accommodated within the said central orifice of said calendar.

It is desirable, but not absolutely necessary, that the said central orifice shall be of a size in proportion to the size of said mouthpiece whereby the same, when in position will frictionally abut against the tubular wall or bushing 8 surrounding said orifice as a preventive against accidental rotary displacing of the casing of said calendar. To facilitate the accommodation of the size of said orifice to any slight variation in the diametrical size of different mouthpieces it may be preferable to make the said wall inclosing said orifice resilient, such as by the tapering of said wall toward the rear end 110

thereof and providing the same with slots or incisions 9 to permit the expansion of said tubular wall when a mouthpiece of sufficient diameter is inserted therein. The additional 5 compressive effort, in this case, of the resilient tubular wall of said central orifice also locks the said outer casing 4, 5 of the calendar against inadvertent rotation upon the telephone.

10 Where the transmitter casing 1 is provided with a rim 2 as shown in the drawings, peripheral clips 10 may be resorted to as a means or as an additional means of securing the casing 4, 5 of the calendar to 15 the telephone, these clips being preferably integral with one or other of the component parts of the said calendar casing and extending rearwardly and inwardly to an extent adapting them to engage with the said 20 rim 2 and thereby prevent movement of the said calendar away from the face of the said transmitter casing, the said clips also having a radial resiliency whereby they will contract upon the said rim to an extent sufficient to prevent any undesirable rotary 25 movement of said calendar casing.

11 is a slot in the lower edge of the calendar casing to permit access to the disk 6 for the purpose of adjusting the same.

30 12 is a ring by which the calendar may

be suspended from a hook upon a wall or the like, if it be desired to use it in this manner.

This invention may be developed under the scope of the following claims without departing from the essential feature of the 25 invention and it is desired that the specification and drawings be read as merely illustrative and not in a limiting sense, except as necessitated by the prior act.

What I claim as my invention is:—

1. A device of the class described, comprising a rotary disk, a casing within which said disk is located, said casing and said disk being centrally orificed, and resilient means forming the peripheral wall of said 45 orifice and supporting said disk.

2. A device of the class described, comprising a centrally orificed disk, a casing inclosing said disk, and a bushing on the front part of said casing, said bushing extending rearwardly through the said central orifice in said disk, and through the back of said casing for the purposes specified, said bushing also being of an expanding 50 nature.

Signed at the city of Toronto, in the county of York in the Province of Ontario, in the Dominion of Canada this 29th day of August, 1916.

BROOK SYKES.
